SHOELACE FASTENING DEVICE

Eugene W. Storey, Philadelphia, Pa.

Application July 2, 1942, Serial No. 449,403

1 Claim. (Cl. 24—117)

My invention relates to a shoelace fastening device and has been conceived with the idea mainly in mind of eliminating the inconvenience, loss of time and hazards associated with the conventional bow knots which are used and frequently come untied at a highly inconvenient or dangerous time.

Heretofore attempts have been made in this field to effect improvement, but to my knowledge the attempts have been costly, complicated, bulky, or unsatisfactory in operation due to the fact that secure fastening may require the tying of a knot in addition to the use of a fastening device. In some instances several of these disadvantages are found in a single device.

Broadly speaking, my main object is to effect improvement in this limited field so as to obviate the disadvantages of the prior art and provide a device which is simple, compact, cheap to manufacture, easy to associate with the desired shoe to be worn, and above all easy to operate and positive in its action without the use of an aiding knot.

A more detailed object of my invention is the provision of a device which may be attached to any lace shoe with little effort and because of its simplicity and compactness it will be scarcely noticeable in the appearance of the ordinary conventional shoe now in use.

Another object of my invention is the provision of a device which may be used in fastening the shoe and then eliminate the familiar difficulties encountered in the dark when the customary bow knot is entangled in the untying process and eventually becomes a hard knot which defies loosening except with long effort and possible resort to tweezers or the like in the presence of light.

Another object of my invention is the provision of a device which is of such character as not to injure the shoes or hose, or the trouser cuff, and even though it is my object to eliminate the necessity of using bow knots and the like, it is still possible for persons who prefer them to simulate them in addition to the fastening device for appearance purposes.

Other more detailed objects and advantages of my invention will appear hereinafter as this description proceeds.

In accomplishing the above objects I provide a device in which two basic principles are employed together to insure rapid and secure fastening. One of these principles is known as "snubbing" and generally may be described as the wrapping of a free end of a taut line around an upstanding stud or post. The other principle

employed is that of clamping, which generally may be described as the application of pressure upon opposing surfaces of an article by a pair of members in the manner of the familiar vise or nutcracker. Further, in uniting these two basic principles I provide a clamping jaw which because of its formation and contour will readily admit the free end of the shoe lace to clamping position, securely hold it after it reaches this position and will also cover layers of the lace which are wrapped around the stud post associated with the clamping jaw.

My invention, therefore, comprises a device of the character described in which I provide an upstanding stud or post, associate a clamping jaw therewith and form the clamping jaw in such manner as to overhang layers of shoelaces wrapped around the stud or post, and yet permit easy entrance of the shoelace to clamping and snubbing position.

My invention may be best understood by reference to the accompanying drawing, in which Figure 1 is a perspective view of a portion of a shoe carrying a shoelace fastener. Figure 2 is a perspective view of the fastener by itself. Figure 3 is a longitudinal sectional view through the fastener and shoe tongue as it is secured in position for use. Figure 4 is a top plan view of the device assembled in operative position with the shoelace in the initial fastening position. Figure 5 is a top plan view of the device with the shoelace attached to a shoe and completely in fastened position.

Referring now to Figures 2 and 3, my device comprises a pedestal base 6 preferably of rectangular shape and provided at each corner with thread receiving openings 7, rounded corners 8 and beveled edges 9.

Upstanding from the base 6 adjacent one end 40 and substantially centrally of the device is a stud or post 10 generally square in cross section and of sufficient height to receive a number of wrappings of shoelace between the base 6 and the clamping member to be described.

At the upper end of the snubbing post 10 a clamping jaw generally indicated at the letter J is carried, and generally speaking in top plan view this jaw is egg-shaped in outline with the smaller end arranged forwardly of the post 10 and the larger end protruding a relatively short distance to the rear of the post.

Due to the shape of the jaw it overhangs the post, as shown in Figures 4 and 5, a substantial distance to provide coverage for wrappings of 55 shoelaces arranged around the snubbing post 10.

As shown more clearly in Figure 3, the top surface of the clamping jaw is substantially arcuate in outline, and at its forward end is rounded and downwardly inclined as at 11 to provide a cam surface or mouth in association with the base 6 to receive the shoelace. At the lower end of the cam surface 11 a hook jaw 12 is formed due to the incline of the same surface, and the rounded cutout 13 on the lower face of the clamping jaw. Between the rounded surface 13 and the post, a substantially horizontal wall extends to define in association with the base a more or less box-like loop for reception of the shoelace.

As shown in Figure 3 also the clamping jaw overhangs the rear of the post and defines in association with the base a U-shaped recess for receiving portions of the shoelace which are wrapped around the post or stub 10.

One way to assemble the device with the ordinary shoe tongue 14 of shoe 15 is to form a small slot 16 running transversely and substantially centrally of the tongue 14 adjacent the top eyelets 17 by a knife or any suitable tool. Thereafter the clamping jaw is inserted into the slot 16 from the lower side of the tongue and pushed upwardly until the major portion of the post is exposed above the surface of the tongue 14. Thereafter the stitches 18 may be formed to sew the base to the tongue and a base cover strip 19 may be cemented over the base to provide a smooth surface for contact with the foot or instep.

As can be seen in connection with Figure 4, the shoelace generally indicated at L is laced in the usual manner and drawn tightly, and the ends 20 and 21 are crossed at the region of the post 10 and each of the ends 20 and 21 is pulled under the cam surface 11 in this crossed relation, and then wrapped around the post 10 so as to be in position to the drawn under the cam surface 11 again with part of the wrapped portions lying beneath the rear end of the clamping jaw J. A single turn of each end of the lace around the post is all that is required, and after the fastening is secure, loops 22 and 23 may be formed and the free ends 20 and 21 may be snapped under the cam surface 11 and the jaw 12 to simulate a bow knot.

The loosening operation for the shoelace is very simple and merely requires for positive operation a slight amount of care if a simulated bow knot is formed. In this operation the loops 22 and 5 23 are permitted to remain open and the portions of the free ends 20 and 21 which are under the clamping jaw are merely pulled forwardly of the 10 jaw to release the clamping effect and then the free ends are wound in a direction reverse to the fastening direction to free them from the snubbing and clamping effects of my device.

From the foregoing description it can be seen that no visual inspection of the shoelace is necessary during the tying or loosening operations 15 and that the frequent entanglements of the customary bow knots may be completely avoided; further, that a very secure fastening of the shoelace is effected in a compact and presentable manner.

I preferably form my device of a material having some resilience such as hard rubber, aluminum alloy, or other material having sufficient strength accompanying resilience to serve my purpose. The resilience of the material aids in giving the desired clamping effect apart from the compressibility of the customary shoelace and facilitates operations in fastenings and loosening.

Various modifications in details may be made 30 without departing from the spirit of my invention, and I wish to avail myself of all variations coming fairly within the scope of the appended claim.

I claim:

25 A device of the character described comprising a base, a snubbing post extending substantially vertically from said base, a clamping jaw carried by said snubbing post in spaced relation to said base and overhanging the same on at 40 least two opposed sides with one end of the clamping jaw extending downwardly toward the base with a cam surface at its outer end to define a mouth in connection with said base and being formed with a hook-like portion at its inner end 45 to hold a shoe-lace between the clamping jaw and the base.

EUGENE W. STOREY.
